UNITED STATES PATENT OFFICE.

EDGARDO FERRATI, OF ROME, NINO PECORARO, OF SPEZIA, AND ALESSANDRO GUIDONI, OF ROME, ITALY, ASSIGNORS TO SOCIETA ANONIMA ITALIANA GIO. ANSALDO & C., OF CORNIGLIANO LIGURE, ITALY.

MEANS FOR THE PROTECTION OF SHIPS, BOTH MERCANTILE AND NAVY SHIPS, AGAINST SUBMARINE ATTACKS OR MINES.

1,299,697.

Specification of Letters Patent.

Patented Apr. 8, 1919.

Application filed July 9, 1918. Serial No. 244,106.

To all whom it may concern:

Be it known that we, Lieut.-General EDGARDO FERRATI, Royal Corps Italian Naval Architects, Lieut.-Colonel NINO PECORARO, Royal Corps Italian Naval Architects, and Major ALESSANDRO GUIDONI, Royal Corps Italian Naval Architects, subjects of the King of Italy, and residing, respectively, at Rome, Spezia, and Rome, Italy (whose 10 post-office address is Ministero di Marina, Rome), have invented certain new and useful Improvements in Means for the Protection of Ships, Both Merchantile and Navy Ships, Against Submarine Attacks or Mines, 15 of which the following is a specification.

The present invention, forming object of this application, relates to improvements in the means of protection of ships against submarine attacks or mines.

As a matter of fact the arming of ships with guns and gunners, the escorting of convoys with warships, the patrolling of the routes and other means until now employed, have given good results, but not sufficiently 25 to completely insure the safety of the ships from submarine attacks.

To neutralize the submarine blockade, it is necessary to provide the ship itself with a protective structure, such as to resist the 30 explosion of one or more torpedoes; and to keep the ship afloat and in good condition of navigability after the same has been struck by a torpedo.

A system which answers the said purpose 35 is the one hereinafter described. It has been designed and practically applied by the inventors with the coöperation of the Royal Navy of Italy.

The system is described and illustrated in 40 one of its forms of application by the accompanying drawing in which:

Figure 1 is a main section through the framing of the air chamber.

Fig. 2, is a main section corresponding to 45 a water tight bulkhead of the air chamber,

Fig. 3 is a horizontal section on the line *a—a* of Figs. 1 and 2.

Fig. 4 is a main transverse section of the ship.

Fig. 5 is a transverse section taken at the 50 bow or the stern of the ship.

In the above figures the form of hull and its structure are as usual in merchant ships, but in the case of naval ship both form of hull and structure will be as are or shall be 55 convenient for such ships.

With reference to the drawings in particular, the protective structure is entirely applied to the outside of the ship, leaving its inside completely free and unaltered so 60 that its loading capacity in volume remains unchanged. Moreover the protective structure weighs less than the water displaced; consequently the draft of the ship is not augmented leaving its dead-weight capacity 65 as it was.

The protective structure in the case of steamers has a temporary character, its *raison d'être* being determined by present war conditions, and to that purpose it is built in 70 such a way as to be easily detached from the ship's hull, to restore it, at the end of the war, to its primitive condition. But it assumes a permanent character of useful application in the case of war ships to which 75 the present application for patent is extended.

The structure is constituted by a reinforced concrete wall —A— applied on the sides of the ship's hull, and by an air chamber —B— fastened over the reinforced concrete wall —A—, such chamber causing a torpedo, striking the vessel, to explode at a certain distance from the concrete wall, so that said wall will be spaced a sufficient distance 85 from the explosion to withstand the blow of the explosion.

The air chamber may be built with any suitable material such as iron steel or other metal, wood and also reinforced concrete. 90 The said chamber may be formed by a series of water tight sections detachably arranged one near to another.

In the form shown by the drawings, the chamber —B—, is provided with several 95 water tight bulk-heads —D— to reduce the portion of the chamber flooded by the explosion of the torpedo.

The wall —A— is externally lined with an iron sheeting —C—, not absolutely necessary, but which may increase the resistance of the concrete wall, and on which the air chamber —B— is applied.

It is well that the wall —A— be molded in a continuous way, without any separation which may diminish the efficiency of the wall itself.

10 The conglomerate constituting the concrete wall may be made with pure cement, cement and sand or cement sand and gravel or minute stones, also of "pozzolana" or any other similar materials with which a good 15 adhesive and resistant conglomerate can be obtained.

To obtain an efficient protection against the explosions of the actual, or of more powerful torpedoes, the reinforced concrete 20 wall should be at least 80 centimeters (about 30") thick, and the air chamber 185 centimeters (about 70"). By increasing the size of wall and of the air chamber a better protection is obtained and vice versa. The 25 structure is applied all along the hull, from stem to stern, and from the keel up to and above the load water line, as it is shown by Figs. 4 and 5.

The hereinbefore described protective 30 system answers very well the purpose for which it was devised and may be applied to any type of ship, mercantile as well as naval. With this improvement the ship is also protected against the explosion of an 35 anchored or floating mines.

The stem and stern bulkheads of the ship are also lined with a thick layer of reinforced concrete to protect the ship's bow and stern to provide for the reduced protection due to the reduced thickness of the 40 structure, to the shape of the ship and to the streamline construction of the structure itself.

The extreme fore and aft chambers may be additionally reinforced with any suitable 45 material or they may be flooded when the ship is passing through danger zones.

Having now particularly described the invention and in what manner the same is to be performed, we declare that what we 50 claim is:

1. Improvements in means for the protection of ships against submarine attacks of torpedoes and mines, constituted by a structure fixed to the outside of the ship's 55 hull all along its sides and from the keel up and above the load water line, the said structure comprising a reinforced concrete wall applied to the ship's hull, and an air chamber applied over the said reinforced concrete wall.

2. Improvements in means for the protection of ships against torpedo attacks and mines, comprising a reinforced concrete wall, and a water tight air chamber of any 65 suitable material, the said air chamber being formed with a plurality of water tight elements easily detachable and changeable, the said elements serving the purpose of exploding a torpedo or mine at a sufficient 70 distance from the reinforced concrete wall to prevent damages to it and consequently to the ship's hull.

In testimony whereof we have hereunto signed our names in the presence of two 75 witnesses.

It is well understood that no royalty of any kind shall be claimed during the present war time for the use of this patent on ships involved in commercial trade.

EDGARDO FERRATI.
NINO PECORARO.
ALESSANDRO GUIDONI.
